US0D1026774S

(12) **United States Design Patent** (10) **Patent No.:** **US D1,026,774 S**
(45) **Date of Patent:** **** May 14, 2024**

(54) **WHEEL**

(71) Applicant: **Wheel Pros, LLC**, Greenwood Village, CO (US)

(72) Inventor: **John Hale**, Compton, CA (US)

(73) Assignee: **Wheel Pros, LLC**, Greenwood Village, CO (US)

(**) Term: **15 Years**

(21) Appl. No.: **29/817,009**

(22) Filed: **Nov. 28, 2021**

(51) LOC (14) Cl. **12-16**

(52) U.S. Cl.

USPC **D12/209**

(58) **Field of Classification Search**

(57) **CLAIM**

The ornamental design for a wheel, as shown and described.

DESCRIPTION

FIG. 1 is a perspective view of a wheel showing my new design; and,

FIG. 2 is a front view thereof.

In the drawings, the broken lines depict portions of the wheel that form no part of the claimed design.

1 Claim, 2 Drawing Sheets
